UNITED STATES PATENT OFFICE

SAMUEL RICHMOND, OF BATAVIA, OHIO, ASSIGNOR TO THE EDWARDS MANUFACTURING COMPANY, OF CINCINNATI, OHIO, A CORPORATION OF OHIO

ROOF STRUCTURE

Application filed October 4, 1927. Serial No. 223,891.

This invention relates to improvements in a roof structure and has for its prime object the production of a metal roofing unit or tile that may be secured to the purlins of a roof structure.

Another object of this invention is to provide a metal roofing unit or tile that is light in weight yet rigid enough to withstand the required wind and snow load.

Another object of this invention is to provide a metal tile that is simple of construction and can be applied or laid by unskilled labor.

These and other objects are attained by the means described herein and disclosed in the accompanying drawings, in which:

Fig. 1 is a perspective view of the metal roofing unit or tile.

Fig. 2 is a fragmental plan view of a roof showing the improved tile in use.

Fig. 3 is an enlarged sectional view taken on line 3—3 of Fig. 2.

Fig. 4 is an enlarged sectional view taken on line 4—4 of Fig. 2.

Fig. 5 is an enlarged sectional view taken on line 5—5 of Fig. 2.

Heretofore roofing tiles or sections have been made that were adapted to be applied to the purlins or rafters of a roof structure but these tiles were made of clay or cement and were very heavy. These heavy tiles required an unusually strong roof structure to support their weight as well as the necessary wind and snow load. Another objection to the clay and cement roofing tiles is that because of their weight they must necessarily be made in small units thereby requiring a large number of units to cover a roof structure entailing the expenditure of a large amount of time and labor. All of these objections have been overcome by the tiles or roofing units of this invention.

The roofing tile or unit 10 is stamped from sheet metal such as copper, zinc or galvanized iron and comprises a pair of corrugations or rolls 11 and 12 formed intermediate its side edges 13 and 14. The upper end of the roll 11 is tapered toward the end edge 15, and the lower end of the roll 12 is tapered toward the end edge 16, as shown at 17 and 18. The upper end of the tile 10 is provided near the edge

15 with a pair of transverse corrugations 19. The tapered portion 17 of the roll 11 is provided with a flat surface 20 upon which the tapered surface 18 of the roll 12 of a tile rests. The edge 13 has a blank strip or tongue 21 formed intermediate itself and the edge of roll 11 for insertion into a suitable lock carried by the adjacent tile. The edge 14 has formed near it a corrugation 22 having a V-shaped cross section. The body 23 of the tile 10 is bent upon itself between the edge 14 and the V-shaped corrugation 22 to provide a groove 24, see Fig. 3. The groove 24 is a lock which receives the tongue 21 for locking or securing adjacent tiles to one another.

The roofing tiles or units 10 are adapted to be secured to the purlins 25 carried by the principal rafters or trusses 26. In laying a roof of this invention the workmen would begin at the left hand corner and apply the first tile. Each tile is provided with a securing strip 27 adjacent to the corrugation 22.

After the first tile has been laid suitable means, such as a wire 28 as shown in Fig. 3, is employed for securing the edge 14 of the tile to the purlins 25. The second tile is now mounted in place by inserting the tongue 21 into the groove 24 of the first tile and securing this tile in the manner as above described.

After the first transverse row of tiles have been laid the second row is started with a half of a tile which causes its locking groove 24 to fall intermediate the ends of the first tile thereby breaking or staggering the joints. The lower end of the corrugation 22 and securing strip 27 is removed, as shown at 29 in Fig. 1, so that the tiles of the second row will receive the roll 12 of the transverse row below, this is clearly illustrated in Fig. 2.

These tiles are made approximately two feet wide and four feet long and may be applied to any roof having end supports not greater than four feet apart as shown in Fig. 4. In other words should the purlins or rafters be spaced four feet apart it would be sufficient support for a roofing unit or tile of this invention. It has been found that No. 22 gauge galvanized steel is sufficiently strong for all conditions and weighs approxi-

mately two pounds per square foot as compared with concrete, cement or clay tiles which would weigh approximately twenty pounds per square foot. It is therefore 5 readily evident that a more economical roof has been produced that will answer the purpose of the expensive roofs used heretofore. It should also be noted that because of the light weight and simplicity of construction 10 of these tiles they can be economically laid by unskilled labor and in a minimum of time. Because of the large size of the tiles a relatively small number of tiles are necessary to completely cover a roof. The entire lower edges 15 16 of the tiles are bent downwardly as shown at 30, to contact the tiles next below and to insure rain and the like descending onto the next tile. The corrugations 19 formed transversely of the tiles 10 form a dam, which prevents wind and snow from being blown upwardly under the tiles, thereby insuring a water-proof roof. Any other means than the wires 28 may be used for fastening the tiles to the purlins such as bolts and nuts, lag 20 screws, expansion screws or the like, or a tongue or lock may be formed upon the tile itself and bent or fastened about the purlins 25 for securing the tile in position.

It is readily evident that these tiles may 30 also be applied over the existing old surface of a roof when it is desired to renovate or resurface said roof.

What is claimed is:

1. A relatively large, light weight, metal 35 roofing unit adapted to have its end edges secured to the purlins of a roof structure comprising a pair of longitudinal rolls formed in the unit intermediate its side edges, one end of each roll being tapered toward its adjacent end edge, transverse corrugations 40 formed in the unit at one end thereof forming a dam when the units are mounted upon one another, and complementary locking means formed along the opposite side edges.
2. A metal roofing unit adapted to have its 45 end edges secured to the purlins of a roof structure and each unit adapted to overlap another unit comprising a pair of longitudinal rolls formed intermediate the side edges of the unit, one end of each roll being tapered toward its adjacent end edge, a transverse corrugation 50 formed in the unit at one end thereof forming a dam when the units are laid in place, a locking tongue formed along one side edge of the unit, and a complementary locking groove formed along the opposite side edge adapted to receive the tongue of the adjacent unit.
3. A metal roofing unit adapted to have its 55 end edges secured to the purlins of a roof structure, and each unit adapted to overlap another unit comprising a pair of longitudinal rolls intermediate the side edges of a unit, one end of each roll being tapered toward its adjacent end edge, a transverse cor-

rugation formed in the unit adjacent one end thereof, a locking tongue formed along one side edge of the unit adjacent one roll, a locking groove formed along the other side edge adapted to receive the locking tongue, a fastening strip adjacent the locking groove, and a depending transverse flange along one end edge of the unit adapted to lie on the upper surface of the underlying unit.

4. A sheet metal roofing plate having one longitudinal edge shaped to interlock into a locking channel in the adjacent plate and the other longitudinal edge being provided with an anchoring flange, a locking channel being formed adjacent to this latter edge, transverse corrugations being formed in the upper end of the plate extending from the locking channel to the lock engaging flange at the other edge, said sheet being provided additionally with a pair of upstanding open longitudinal rolls, one roll extending from the lower edge of the plate to a point near the upper edge where it is tapered off, and the other roll extending from the top edge of the plate to a point near the lower edge of the plate, this latter end of the roll being tapered off.

5. A sheet metal roof structure comprising a plurality of similar roofing plates arranged for watertight interlocking one upon another along their longitudinal edges, a pair of longitudinal rolls extending from top to bottom edge of each plate, one roll being disposed centrally of the plate and tapered at an end to the bottom of said plate, the other roll being disposed adjacent a lateral edge of the plate and tapered at an end to the top of the plate, transverse corrugations parallel to the top of the plate and extending across the rolls, and a down-turned bottom edge on the plate extending across the rolls, said edge being adapted to overlap and abut a corrugation on the top of a plate next below to provide a uniform seal between such plates, the adjacent tapered ends of the rolls on such plates being received one in the other to effect staggering of the interlocked longitudinal edges in successive rows of plates.

In testimony whereof, I have hereunto subscribed my name this 16th day of September, 1927.

SAMUEL RICHMOND.
